UNITED STATES PATENT OFFICE.

JACOB GARRETT KEMP, OF STILLWATER, OKLAHOMA, ASSIGNOR OF ONE-HALF TO
MONROE JOE OTEY, OF STILLWATER, OKLAHOMA.

CHECK.

1,272,340.

Specification of Letters Patent.

Patented July 9, 1918.

Application filed October 12, 1917. Serial No. 196,230.

To all whom it may concern:

Be it known that I, JACOB GARRETT KEMP, a citizen of the United States, residing at Stillwater, in the county of Payne and State 5 of Oklahoma, have invented new and useful Improvements in Checks, of which the following is a specification.

This invention relates to a check and check book and it consists in the novel features 10 hereinafter described and claimed.

An object of the invention is to provide a check and check book especially adapted for what is generally known as "Odd-change savings check book." This book is to be 15 used by banks with saving and checking departments and may be used by banks desiring to use the system for the convenience of their customers by carrying a special odd-change account instead of the odd-change 20 savings account.

Briefly the check may be used as follows:—

A check is drawn on the checking account to be in full number of dollars, that is no 25 cents, while the check made payable to John Doe, is to be whatever amount required, for example, two hundred dollars and seventeen cents. A space is provided upon the check for writing this amount in script and in 30 numbers while a space is provided for writing in script and numbers the next higher whole number of dollars. That is to say—two hundred and one dollars, which is the maximum amount and in excess of the exact 35 amount called for by the check. When presented for payment at the bank, the check is canceled and two hundred and one dollars deducted from the check account while eighty-three cents is deposited in the savings 40 account or in the odd-change account. The advantages gained by this form of check and check book are that it decreases the possibility of error in keeping the checking account and of the check being raised. The 45 customer is not required to consider the cents in addition and subtraction as this is done by the experts at the bank. The customer need not forward the balance since the stub of the preceding check can be slipped upward or turned until the balance is in position on the next stub. The stub is provided with spaces to keep the odd change or savings account and check account. This form of check book and system will encourage the

saving habit and cause very large increase 55 in the business of savings department.

In the accompanying drawing:—

The figure is a plan view of the check and stub.

The check and stub hereinafter described 60 may be bound together in the form of leaves of a check book, and the check indicated at 1 is provided with the name of a bank indicated at 2 and the location of the bank shown at 3 and a space 4 for the entry of a date. 65 The check also bears a space 5 in which the name of a payee may be entered, a space 5' in which the exact amount payable by the check may be entered in script, also a space 6 in which the amount may be entered in 70 script, the said amount being a maximum amount of whole dollars and in excess of the exact amount called for by the check. The difference between the maximum amount stated and the exact amount is transferred 75 by the bank official from the depositor's checking account to his savings account. The check also bears a space 7 in which the name of the payor may be entered. The check 1 also bears a space 8 in which may 80 be entered in figures the maximum amount in whole dollars which amount is in excess of the exact amount called for by the check. Immediately below the space 8 the check 1 is provided with a space 9 in which may be 85 entered in figures the exact amount called for by the check. Immediately below the space 9 the check is provided with a space 10 in which may be entered in figures the difference between the maximum excessive 90 amount and the exact amount called for by the check.

A stub 11 is detachably connected with the check 1 and has spaces in which may be entered the date, the name of the payee, 95 the purpose for which the amount is paid and the exact amount of the check. The stub also bears a column 12 which is indicated as a savings column and a column 13 which is indicated as a checking column. 100 These columns are horizontally lined whereby spaces are provided in both of the said columns in which may be entered "Balance forward," "Amount deposited," "Total," "Amount of this check," and "Balance." 105

Having described the invention what is claimed is:—

A check having the identification of a

financial institution thereon and provided with spaces for the entry of the names of a payor and payee, a maximum payable amount specified in script thereon, an exact 5 payable amount specified in script thereon, column spaces thereon, the maximum amount entered in figures at the tops of said

spaces, the exact amount entered in figures in said column spaces below the first mentioned figures, and the difference between 10 the two sets of figures entered in the spaces below the second mentioned figures.

In testimony whereof I affix my signature.
JACOB GARRETT KEMP.
